United States Patent Office

Des. 198,409
Patented June 9, 1964

198,409

WATERPROOF CONTAINER OR SIMILAR ARTICLE

Frederick Ehrsam, Rte. 662, Oley, Pa.

Filed July 17, 1962, Ser. No. 70,954

Term of patent 14 years

(Cl. D58—11)

FIG. 2.

FIG. 1.

FIG. 3.

FIGURE 1 is a side elevation view of a waterproof container or similar article showing my new design; and,

I claim:

The ornamental design for a waterproof container or similar article, as shown.
